REFUSE DISPOSAL APPARATUS

Harry Higer, Detroit, Mich.

Application September 8, 1951, Serial No. 245,680

4 Claims. (Cl. 146—108)

1

This invention relates to a garbage disposing apparatus, which is used in conjunction with the water drainage from a building to a sewer. More particularly, this invention pertains to a novel disposal apparatus, which is particularly adapted for the disposing of certain articles which heretofore could not be properly handled by present disposal apparatus of this type.

It is the object of this invention to provide a disposal apparatus, which is particularly adapted for the cutting up and disposing of feathers from fowl such as, chicken feathers, as well as other refuse which heretofore has not been conveniently disposed of in presently available disposal apparatus.

It is the further object of the invention to provide a novel and simple disposal apparatus which may be used in conjunction with a sink and wherein the material, such as feathers, may be fed thereto, compressed and moved into the path of rotating cutting blades for chopping the same into short easily disposable elements.

These and other objects will be seen from the following specification and claims in conjunction with the appended drawings in which—

Fig. 1 is a top plan view of the disposal apparatus with the cover removed, being a section taken on line 1—1 of Fig. 3.

Fig. 2 is a section taken on line 2—2 of Fig. 3.

Fig. 3 is a side elevational view of the apparatus with one sidewall removed for illustration and with the end walls and cover portions in section, together with a diagrammatic illustration of the electrical connections employed.

Fig. 4 is a section taken on line 4—4 of Fig. 2.

Fig. 5 is a plan view of the disposal apparatus; and

Fig. 6 is a fragmentary section taken on line 6—6 of Fig. 4.

It will be understood that the above drawings illustrate merely a preferred embodiment of the invention, and that other embodiments are contemplated within the scope of the claims, hereinafter set out.

Referring to the drawing, the present disposal apparatus includes the end walls 11 and 12 and the side walls 13 and 14 as in Fig. 1 together with the top wall 15, which thus provides a complete enclosure for the apparatus.

As shown in Fig. 3 top wall 15 is partially cut away to define the inner ledges 16 which border a central opening formed in member 15, and upon which is supported openable cover 17 with its handle 18. An additional cover element 19 with its handle 20 is also supported upon the ledges 16 and is hinged as at 21 to cover 17. By this construction either of the covers 17 or 19 may be separately opened to permit access to the interior of the disposal mechanism, or on the other hand, the covers 17 and 19 may be entirely removed.

2

As shown in Figures 3 and 4 there are provided at least a pair of horizontal angle irons 22 and upright angle irons 23 together with a platform element 24 to thereby provide a support for the motor 57 and the other mechanisms associated therewith.

Upright supports 25 and 26 extend upwardly from portions of the platform 24 and supportably engage the main roller housing through which the material to be disposed of is directed. Said roller enclosing housing includes the downwardly inclined bottom wall portion 27 which terminates at its upper end at the upwardly curved front wall portion 28. Said housing also includes the parallel spaced sidewall elements 29 and 30 to thereby complete the roller housing.

Referring to Fig. 6 the sidewalls 29 and 30 of said housing have a plurality of upright longitudinally spaced slots 31 which are adapted to receive the vertically adjustable bushings 32. Said bushings have formed in their opposite sidewalls the upright slots 33 which cooperatively receive the corresponding wall portions of the walls 29 and 30 which bound the upright slots 31.

The three roller supporting shafts 34, 35 and 36 are journaled through bushings 32 as shown in Fig. 6 and are driven in the manner hereinafter described.

The forward roller 37, preferably of a sprocket shape and constructed of rubber or an equivalent material, is supportably secured upon the shaft 34. The second material engaging roller 38, preferably formed with a series of elongated sprocket elements is secured upon shaft 35. The third preferably rubber roller 39 is secured upon shaft 36, by any suitable means as for example, a key 40 as shown in dotted lines in Fig. 6.

By this construction the three rollers 37, 38 and 39 are journaled within the enclosing housing 29—30—27—28 and are adapted to vertical adjustments within the upright slots 31 by virtue of the connections of bushings 32 therewith.

Upright scraper blades 41 are arranged forwardly of each of the rollers and extend across the interior of the roller housing, and have upright end wall portions 42 which are secured to the bushings 32 as shown in Fig. 6.

As shown in Fig. 4 the scraper blades 41 include the rearwardly directed transverse blades 43 which are upturned slightly as at 44 into close proximity to said rollers to prevent the material from being carried along by the rollers and, at the same time, providing guide passages 46 for the material below the transverse plates 43 relative to the interior surface of the bottom wall 27.

As shown in Fig. 6 the end scraper blade 41 has lateral extensions 45 which extend across the upright ends of the sidewalls 29 and 30 to thereby provide a partial closure at that end of the roller housing. It will be noted from Fig. 4 that the

horizontal portion 43 of the last scraper blade 41 is spaced above the bottom wall 27 to thereby define the throated outlet 47 for the material as it is moved along the bottom wall 27 of the roller housing by said rollers.

As shown in Fig. 4 the material which is moved by the rollers through the throated opening 47 is projected into the path of rotating cutting blades 60', hereafter described, so that the material, such as chicken feathers, will be cut up into small particles and will be washed downwardly through the outlet passage 48, which is arranged forwardly of the throated opening 47 and to which is connected the sewer drain pipe 49.

As shown in Figures 1 and 2 the roller housing sidewalls 29 and 30 terminate at their upper ends in the horizontal out-turned elongated flanges 50. These flanges have formed therein transverse slots which register with the upper ends of the sidewall slots 31 to permit the insertion or removal of the rubber rollers 37, 38 and 39 and their associated bushings and scrapers.

As shown in Fig. 1, wherein the cover has been removed, these transverse slots in flanges 50 are covered by the rectangular plates 51 which are secured to said flanges by a plurality of screws 52. The threaded bolts 53 are threaded down through plates 51 and are in axial alignment with the sockets 55 secured upon the bushings 32 which are adapted to receive the lower ends of the coiled springs 56. Extension rods 54 form a part of the bolts 53 and retainingly extend down into the upper ends of the springs 56.

By this construction it is apparent that each of the rollers is urged downwardly by the springs 56 within the respective guide slots 31 and further that the rollers are so mounted as to be adapted for vertical movements depending upon the action of the rollers upon the material being moved downwardly through the roller housing by said rollers.

It will be also noted from Figures 2 and 5 that there are a plurality of rectangular openings 53' formed in the cover member 17 and through which the heads of the bolts 53 extend. Thus, the cover 17 may be opened without interfering with the mounting of the bolts. Furthermore it is apparent that the bolts 53 may be adjusted to regulate the tension in the springs 56.

Referring to Figures 1 and 3 the electric motor 57 is suitably mounted and secured upon the platform 24. Its elongated shaft 58 is journaled through the bearings 59 which are supported upon platform 24 and secured thereto as at 59'.

The wheel 60 is arranged in an upright plane within the chamber 48 and its hub 62 is suitably secured upon the end of motor shaft 58. Said wheel includes a plurality of curved cutting blades 60' with sharpened leading edges 61 which are arranged closely adjacent the throated material outlet opening 47. Said blades, secured at their ends at 62' to the wheel 60 and its hub 62, are adapted to cut off the material as it is moved out of the opening 47 whence said material is washed down the outlet passage 48 and into drain pipe 49.

Motor shaft 58 has an extension 63 which projects from the opposite side of motor 57 and has a suitable gear secured thereon, such as the gear 63'. This gear is in mesh with a larger gear 64 secured on shaft 65 which is journaled through the bearing support 66 secured on platform 24 at points 67. And the shaft 65 has a drive pulley 68 thereon. Roller operating shaft 34 has a pulley wheel 69 thereon which is interconnected 70

with pulley 68 by the belt 70. Shaft 34 has a second pulley 71 which is connected with pulley 72 on roller shaft 35 by the belt 73.

The second pulley 74 on roller shaft 35 is connected by a belt 76 to pulley 75 on roller shaft 36. Thus, the motor 57 is capable of driving all three of the rollers 37, 38 and 39 by the pulley and belt arrangement shown in Fig. 1.

As it is contemplated that shaft 34 will have some vertical adjustments in view of its mounting, the pulley 70 is sufficiently flexible as to permit such vertical adjustments of shaft 34. In the event that there is too much slack in belt 70, it is contemplated that there may be any suitable means employed in connection with said belt for taking up the slack.

Referring to Fig. 4 the forward portion of the chambered member 29-30 has a substantially upright inlet passageway 77 through which refuse, such as feathers or other materials, may be introduced. Under the action of the rollers and the water, this material is delivered into the compartment 78 occupied by the rollers and moves under said rollers in the manner illustrated in the drawings. A rectangular gate 79 is shown in Fig. 4 hinged along its upper edge at 80 to the under-surface of the cover 17, being positioned within the chambered member or housing 27-28-29-30. The gate 79 is inclined as shown in Fig. 4 and rests against the edges of the roller 37 and tends to guide the material towards the lower portion of said roller and thereunder, and prevents the material from entering the upper portion of chamber 78.

The water supply pipe 81 has a solenoid operated control valve 82 thereon, and said pipe extends as shown in Figs. 3 and 4 throughout the length of the exterior housing adjacent sidewall 14 upon the exterior of the chambered member 29-30. A plurality of transverse parallel spaced pipe extensions 83 are joined at their one ends to the main supply pipe 81 and extend through the sidewall 30 of the roller housing and substantially across said housing to a point adjacent the opposite wall 29. And said pipes 83 which are perforated throughout their lower portions at 84, are closed at their outer ends as shown in Fig. 2 at 83'.

Referring to Fig. 3 there is a diagrammatic illustration of the electrical connection for operating the motor 57, as well as the solenoid 92 which controls valve 82 and which is energized for turning on the water at the same time as the motor begins to operate. The lead wire 87 is connected to one power line 88 and at its other end joins the push button switch 89. A pair of wires 90 interconnect switch 89 and motor 57. The return wire 90 is joined to a safety switch 91 which is shown open in Fig. 3; but said switch, also shown in Fig. 4 will be closed when the cover 17 is in place. The return lead 90 from switch 91 goes to solenoid 92 and the return wire 93 from said solenoid is joined to the second power line or ground wire 85 to thereby complete the electrical circuit. Thus, pushing the switch 89 to "on position" will not energize the motor 57 unless the switch 91 is closed by the cover 17 being in place. With switch 91 closed, it is clear that solenoid 92 will be simultaneously energized to permit the flow of water under pressure through the supply pipe 81 to thereby flush the compartments 77 and 78 and 48 throughout the operation of the motor and the rollers, 37, 38 and 39 connected thereto. Naturally, the wheel 60

with its cutting blades 60' will be simultaneously operated.

While in the preferred embodiment of the invention there has been shown in the drawing a rotatable wheel 60 with curved blades 60' adapted for movement closely adjacent and across outlet opening 47, nevertheless it is contemplated that any other type of movable cutting blade could be employed as for instance, a motor driven vertically reciprocal blade.

Having described my invention reference should now be had to the claims which follow for determining the scope thereof.

I claim:

1. In a refuse disposal apparatus, a chambered member having a downwardly inclined bottom wall, an upright inlet passageway at one end of said member, a downwardly depending outlet passageway beyond the lower end of said bottom wall adapted for communication with a sewer drain, a plurality of longitudinally spaced rollers journaled within said chambered member transversely of its length spaced above and cooperable with said bottom wall for moving said refuse down said bottom wall towards said outlet passage, rotatable cutting blades journaled within said outlet passage closely adjacent the end of said bottom wall and movable in a plane parallel to the axes of said rollers for cutting said refuse into short strips which drop through said outlet passage, horizontal rectangularly shaped scrapers below forward portions of each roller arranged forwardly of each roller throughout its length and adjacent thereto and spaced from said bottom wall for guiding said refuse to said outlet passage, and an upright supporting plate on each of said scrapers arranged forwardly of said rollers throughout their length and adjustably secured to the side walls of said chambered member.

2. In a refuse disposal apparatus, a chambered member having a downwardly inclined bottom wall, an upright inlet passageway at one end of said member, a downwardly depending outlet passageway beyond the lower end of said bottom wall adapted for communication with a sewer drain, a plurality of longitudinally spaced rollers journaled within said chambered member transversely of its length spaced above and cooperable with said bottom wall for moving said refuse down said bottom wall towards said outlet passage, rotatable cutting blades journaled within said outlet passage closely adjacent the end of said bottom wall and movable in a plane parallel to the axes of said rollers for cutting said refuse into short strips which drop through said outlet passage, a plurality of parallel spaced laterally perforated water pipes extending across and adjacent upper portions of said chambered member at spaced points throughout its length and across the upper portion of said outlet passage for supplying water to said inlet passage, to said rollers and to said outlet passage, and a fluid delivery pipe supported upon the exterior of one of the side walls of said chambered member and connected respectively with said perforated pipes.

3. In a refuse disposal apparatus, a chambered member having a downwardly inclined bottom wall, an upright inlet passageway at one end of said member, a downwardly depending outlet passageway beyond the lower end of said bottom wall adapted for communication with a sewer drain, a plurality of longitudinally spaced rollers journaled within said chambered member trans-

versely of its length spaced above and cooperable with said bottom wall for moving said refuse down said bottom wall towards said outlet passage, rotatable cutting blades journaled within said outlet passage closely adjacent the end of said bottom wall and movable in a plane parallel to the axes of said rollers for cutting said refuse into short strips which drop through said outlet passage, a water supply pipe on the exterior of said chambered member, a plurality of laterally perforated water pipes joined to said supply pipe and extending across and adjacent upper portions of said chambered member for supplying water to said inlet passage, to said rollers and to said outlet passage, a valve in said supply pipe, a solenoid for opening said valve, an electric motor for driving said rollers and said blades, a push button switch, and an electrical circuit from a power source to said motor, switch and solenoid.

4. In a refuse disposal apparatus, a chambered member having a downwardly inclined bottom wall, an upright inlet passageway at one end of said member, a downwardly depending outlet passageway beyond the lower end of said bottom wall adapted for communication with a sewer drain, a plurality of longitudinally spaced rollers journaled within said chambered member transversely of its length spaced above and cooperable with said bottom wall for moving said refuse down said bottom wall towards said outlet passage, rotatable cutting blades journaled within said outlet passage closely adjacent the end of said bottom wall and movable in a plane parallel to the axes of said rollers for cutting said refuse into short strips which drop through said outlet passage, a water supply pipe on the exterior of said chambered member, a plurality of laterally perforated water pipes joined to said supply pipe and extending across and adjacent upper portions of said chambered member for supplying water to said inlet passage, to said rollers and to said outlet passage, a valve in said supply pipe, a solenoid for opening said valve, an electric motor for driving said rollers and said blades, a push button switch, and an electrical circuit from a power source to said motor, switch and solenoid, a cover hinged upon said chambered member, and a normally open switch in said electrical circuit and mounted upon said chambered member and closable upon closing of said cover.

HARRY HIGER.
